Primary Examiner — Dana K Weiland*Assistant Examiner* — Jenny lou M Binas(74) *Attorney, Agent, or Firm* — Bayramoglu Law Offices LLC(57) **CLAIM**

The ornamental design for a vacuum cleaner, as shown and described.

DESCRIPTION

FIG. 1 is a perspective view of a vacuum cleaner showing my new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines shown in the drawings depict portions of the vacuum cleaner that form no part of the claimed design.
